UNITED STATES PATENT OFFICE

2,503,437

VERTICAL OVEN

Vernie A. Fox, Detroit, Mich.; assignor, by mesne assignments, to Young Brothers Company, Detroit, Mich., a corporation of Michigan

Application December 31, 1946, Serial No. 719,540

8 Claims. (Cl. 34—66)

1

This invention relates to drying ovens, and in particular to vertical drying ovens.

One object of this invention is to provide a vertical drying oven wherein the articles to be dried are carried by an endless vertical conveyor and cooling air is forced into the oven near the unloading end of the conveyor in a direction opposite to the direction of motion of the conveyor.

Another object is to provide a vertical drying oven, as set forth in the preceding object, wherein the air within the oven is heated by a heat exchanger and forced upward in a direction contrary to the direction of motion of the conveyor.

Another object is to provide a vertical drying oven, as set forth in the preceding objects, wherein a portion of the cooling air is bled off before being heated, by being withdrawn from the oven through an escape duct or stack.

Another object is to provide a vertical drying oven, as set forth in the preceding objects, wherein means is provided for recirculating the heated air within the oven housing past the heat exchanger in such a manner that much of the air within the housing is used over and over again, but is constantly added to by the fresh air introduced for cooling purposes.

Other objects and advantages of the invention will become apparent during the course of the following description of the accompanying drawings, wherein:

Figure 1 is a vertical section through a vertical drying oven, according to a preferred form of the invention, with the conveyor in side elevation;

Figure 2 is a transverse fragmentary vertical section taken along the line 2—2 in Figure 1, and

Figure 3 is a horizontal section taken along the line 3—3 in Figure 1, immediately above the heat exchanger.

Referring to the drawing in detail, Figures 1 and 2 show a preferred form of the vertical drying oven generally designated 10 as including an elongated vertical housing 11 in the form of a hollow column having a loading opening 12 and an unloading opening 13 on the opposite sides of the housing 11 near the bottom thereof. Mounted within the housing 11 is an endless conveyor, generally designated 14, for conveying the workpieces to be dried from the loading station adjacent the loading opening 12 to the unloading station adjacent the unloading opening 13.

The conveyor 14 consists of endless chains 15 (Figure 2) arranged in substantially parallel vertical planes and having U-shaped hangers 16

2

pivottally connected thereto as at 17 and carrying horizontal shelves 18 for receiving and conveying the workpieces to be dried. The conveyor chains 15 at the bottom of the oven housing 11 encircle and mesh with spaced sprockets 19 mounted on a horizontal shaft 20 which is journaled in bearing brackets 20a extending upward from the floor 21 at locations outside the oven housing 11.

At the tops of their runs, the conveyor chains 15 encircle and mesh with similar spaced sprockets 22 (one only being shown) mounted on a shaft 23 journaled in the opposite sides of the housing 11. The shaft 23 is driven so as to rotate in the direction of the solid arrow by any suitable means, such as, for example, by the pulley 24 mounted on the shaft 23 and driven by the belt 25 from an external source of power such as an electric motor and reduction gear unit. The pulley 24 and belt 25 are shown merely for simplicity of illustration, whereas in actual practice the shaft 23 is preferably driven through gearing connected thereto.

Extending substantially from the bottom to the top of the conveyor 14 and across the space between the sprockets 19 and 22 is a baffle or partition structure, generally designated 26 and including a lower baffle 27 with a transversely bent upper portion 28 engaging an upper baffle 29 having a transversely bent lower portion 30 engaging the lower baffle 27. The baffles 27 and 29 with their portions 28 and 30 enclose a heating chamber 31 having an intake port 32 at the bottom and one or more discharge ports 33 at the top thereof.

Mounted in the heating chamber 31 is a heat exchanger 34 (Figure 1) which is heated by a heater 35, such as a gas burner, oil burner, steam pipe or electric heater. Connected to each discharge port 33 is the discharge duct 36 of one or more exhaust fans 37, each having a casing 38 with an intake port 39 and a shaft 40 with one or more bladed rotors. The shaft 40 is driven by an electric motor 41a (Figure 2) which, while shown for simplicity as adjacent a single fan 37, in practice is preferably mounted outside the oven housing 11, driving the shaft 40 of several fans 37 mounted in tandem. The fan 37 draws in air through the intake port 32, causes it to be heated as it passes the heat exchanger 34 and discharges it through the discharge duct 36 into the upper portion of the oven housing 11. The thus heated and recirculated air passes upward in the direction of the arrows, and in the opposite direction to the direction of travel of the conveyor 14, drying the workpieces traveling

downward on the shelves 18 of the work supports 16.

The heated air passes over the top of the upper baffle 29, and downward on the other side thereof, still traveling in the opposite direction to the direction of travel of the conveyor 14. The downwardly-traveling air passes through the intake port 32 into the heating chamber 31 in response to the suction created by the fan 37 and is reheated as it passes upward along the walls of the heat exchanger 34 whence it is again drawn into the eye 39 of the fan 37 and discharged through the discharge port 33 into the interior of the oven housing 11. In this manner the air passing through the interior of the oven housing 11 is reheated and recirculated repeatedly.

In order to cool the workpieces on the shelves 18 of the hangers 16 as they near the unloading station adjacent the unloading opening 13, and also to provide added fresh air to be mixed with the heated air within the housing 11, the latter above the unloading opening 13 is provided with an air intake port 42 (Figure 1) to which is connected an upwardly inclined cool air intake duct 43. Mounted in the intake port 44 of the duct 43, as by the brackets 45, is an air intake fan 46 having blades 47 mounted on a shaft 48 driven by an electric motor 49. The rotation of the fan blades 47 draws in fresh air from the outside of the oven housing 11 and forces it upward through the duct 43 and port 42, cooling the articles on the shelves 18 as the latter near the unloading opening 13.

The housing 11 above the intake port 42 is provided with a discharge or bleed-off port 50 to which is connected a bleed-off or discharge duct or stack 51 (Figure 1). A portion of the air forced into the housing 11 through the duct 43 by the fan 46 is bled off or withdrawn through the port 50 by the draft created by the stack 51 after it has cooled the articles on the shelves 18. The remainder of the fresh air introduced by the fan 46 passes upward and mixes with the heated air emerging from the heating chamber discharge port 33, thus supplying a small portion of fresh air for replenishing portions of heated air lost from the housing 11, such as that which is exhausted by the fan 55 described below.

In order to assist the downward travel of the heated air within the housing 11 and to withdraw a portion of the heated air therefrom, the housing 10 is provided with an outlet 52 a short distance above the loading opening 12. Connected to the outlet 52 is the suction duct 53 leading to the eye or intake port 54 of a suction fan or blower 55. The latter is provided with a shaft 56 carrying a rotor 57. The latter is provided with the usual blades or vanes (not shown) and rotates within a casing or volute 58, discharging the air through the discharge duct 59.

In the operation of the invention, a part of which has already been described in connection with the description of the construction of the oven 10, the fans 37, 46 and 55, and the conveyor 14 are started in operation and the heat exchanger 34 is heated, such as by steam reaching it through the pipe 35. The shelves 18 of the hangers 16 are loaded through the loading opening 12 with the workpieces to be dried. These workpieces may consist, for example, of sand cores, metal plates or other articles which require drying or which have been coated with various liquids such as paints, or inks. The workpieces

on the shelves 18 pass upward adjacent the left-hand wall of the oven housing 11 (Figure 1). As the articles pass upward, they encounter the descending blasts of heated air which is being drawn downward by the combined action of the fans 37 and 55. The articles on the shelves 18 are thus dried and the drying action continues as they pass over the upper shaft 23 and travel downward until they arrive approximately opposite the upper baffle portion 28. Meanwhile the heated air in the housing 11 is reheated and recirculated by the heat exchanger 34 and fan 37 so that the workpieces are dried in a rapid, efficient and economical manner. At this point they encounter the upwardly-traveling blast of cool air introduced through the cool air duct 43 by the fan 46 and are thereby cooled sufficiently to permit handling at the time they arrive opposite the unloading opening 13. Here they are unloaded and the empty hangers 16 and shelves 18 pass under the lower shaft 20 to reach the loading station. At the loading station, the shelves 18 are reloaded and the foregoing cycle is repeated.

As previously stated, only a portion of the cool air introduced by the fan 46 is utilized to replenish the air drawn out of the housing 11 by the fan 55, the remainder thereof being bled off through the port 50 and stack 51 and discharged into the atmosphere. In this manner the workpieces on the moving shelves 18 are subjected to a hot blast of air traveling in the opposite direction, until they approach the unloading station, where a cool blast of air cools them for the remainder of their travel.

What I claim is:

1. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers, a heat exchanger in said passageway, and a power-driven air recirculation fan mounted adjacent one of said baffle structure ports and arranged to draw air from the ascending chamber through said passageway past said heat exchanger into the descending chamber whereby to recirculate and reheat the air in said housing.

2. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers, a heat exchanger in said passageway, and a power-driven air recirculation fan mounted adjacent one of said baffle structure ports and arranged to draw air from the ascending chamber through said passageway past said heat exchanger into the descending chamber whereby to recirculate and reheat the air in said housing, said air supply fan discharging cool air upward into said descending chamber near the bottom thereof for cooling the articles descending on said conveyor, and a cool air bleed-

off duct opening out of said descending chamber above the connection thereto of said air supply fan.

3. A drying oven comprising an elongated vertical housing, a conveyor mounted for travel along ascending and descending paths in said housing, air supply and exhaust mechanisms connected to said housing, a vertically-extending baffle structure dividing said housing vertically into conveyor-ascending and conveyor-descending chambers, said baffle structure having an air passageway therethrough, a heat exchanger in said passageway, and an air moving device connected to said passageway to draw air from one chamber through said passageway past said heat exchanger into the other chamber whereby to recirculate and reheat the air in said housing, said air supply mechanism having a discharge duct inclined upward into said housing and discharging cool air upward into said descending chamber near the bottom thereof for cooling the articles descending on said conveyor.

4. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers, a heat exchanger in said passageway, and a power-driven air recirculation fan mounted adjacent one of said baffle structure ports and arranged to draw air from said ascending chamber through said passageway past said heat exchanger into said descending chamber whereby to recirculate and reheat the air in said housing, said air supply fan discharging cool air upward into said descending chamber near the bottom thereof for cooling the articles descending on said conveyor.

5. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers, a heat exchanger in said passageway, a power-driven air recirculation fan mounted adjacent one of said baffle structure ports and arranged to draw air from said ascending chamber through said passageway past said heat exchanger into said descending chamber whereby to recirculate and reheat the air in said housing, said air supply fan discharging cool air upward into said descending chamber near the bottom thereof for cooling the articles descending on said conveyor, and a cool air bleed-off duct opening out of said descending chamber above the connection thereto of said air supply fan.

6. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air pas-

sageway therethrough with inlet and outlet ports communicating respectively with said ascending and descending chambers including an enclosure with a bottom inlet from said ascending chamber and a top outlet into said descending chamber, a heat exchanger in said passageway, and a power-driven air recirculation fan mounted adjacent one of said baffle structure ports and arranged to draw air from the ascending chamber through said enclosure past said heat exchanger into the descending chamber whereby to recirculate and reheat the air in said housing.

7. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers including an enclosure with a bottom inlet from said ascending chamber and a top outlet into said descending chamber, a heat exchanger in said passageway, and a power-driven air recirculation fan mounted adjacent one of said baffle structure ports and arranged to draw air from the ascending chamber through said enclosure past said heat exchanger into the descending chamber whereby to recirculate and reheat the air in said housing, said air supply fan discharging cool air upward into said descending chamber near the bottom thereof for cooling the articles descending on said conveyor.

8. A drying oven comprising an elongated vertical housing, a conveyor mounted for travel along ascending and descending paths in said housing, air supply and exhaust fans connected to said housing, a vertically-extending baffle structure dividing said housing vertically into conveyor-ascending and conveyor-descending chambers, said baffle structure having an air passageway therethrough with inlet and outlet ports communicating respectively with said ascending and descending chambers including an enclosure with a bottom inlet from said ascending chamber and a top outlet into said descending chamber, a heat exchanger in said passageway, a power-driven air recirculation fan mounted adjacent one of said baffle structure ports and arranged to draw air from the ascending chamber through said enclosure past said heat exchanger into the descending chamber whereby to recirculate and reheat the air in said housing, and a cool air bleed-off duct opening out of said descending chamber above the connection thereto of said air supply fan.
